WESTERN ELECTRIC COMPANY, OF NEW YORK, N. Y., A CORPORATION OF
ILLINOIS.

SELECTOR FOR MACHINE-SWITCHING TELEPHONE SYSTEMS.

1,131,811.

Specification of Letters Patent. Patented Mar. 16, 1915.

Application filed December 28, 1912. Serial No. 739,054.

To all whom it may concern:

Be it known that I, FRITZ ALDENDORFF, a subject of the King of Great Britain, residing at Vieux Dieu, near Antwerp, Belgium, have invented certain new and useful improvements in Selectors for Machine-Switching Telephone Systems; and I do hereby declare the following to be a full, clear, and exact description of the invention, such as will enable others skilled in the art to which it appertains to make and use the same, reference being had to the accompanying drawing, and to figures of reference marked thereon, which forms a part of this specification.

The selectors forming the subject of this invention are adapted particularly for use in satellite or private branch exchange systems in which a telephone user may sometimes wish to establish a connection through the connecting apparatus of a main or distant exchange and at other times desires a connection through the switching devices of a local or private exchange.

The object of the invention is to enable a telephone user to automatically obtain connection at will with a free trunk leading to the connecting devices of either one of several offices, a group of trunks being provided for each office and several such groups being connected to the fixed selector contacts of one and the same row. To attain this object the test circuits of the selector are placed under the control of the subscriber connected to it and means are provided by which the subscriber, after the selector has selected an idle trunk in the first group, can restart the advance of the selector brushes to the next group without hunting, that is, by rendering the test circuit in this group inoperative. When the brushes reach the second group they will again commence to automatically hunt for an idle trunk line in this group.

One feature of the invention consists in the manner in which the controlling station is enabled to cause changes in the test circuit of a trunk-hunting selector over a metallic circuit without using the earth or a third conductor as a return conductor. This is accomplished by so arranging the testing device of the selector that it connects a switching magnet or relay between the limbs of the controlling line at the moment the

selector finds a free trunk. If the free trunk found is one of a group desired by the party making the call the switching relay is caused to disconnect itself from the line at the moment when the loop leading to the controlling station is momentarily opened in sending the selecting impulses that direct the movements of further selectors used to build up the connection. If the trunk hunting selector is to be caused to travel on to another trunk group, the resistance of the loop is reduced at the controlling station and the ensuing increase of current strength brings about a change of the test circuits of the selector, which causes the same to travel over all the contacts of a group and not to commence testing until it has reached another group. The switching device that effects the circuit changes of the test circuits and that is connected between the limbs of the controlling line may consist of a relay having contacts some of which are actuated on the passage of a comparatively feeble current through the coils of the relay and others that require a stronger current to move them.

Another feature of the invention consists in leading each of the groups of trunks of the various groups of contacts to a separate telephone system, each of the different systems being excluded from communication with each other. By providing some telephone users with a trunk hunting selector giving access to several groups of trunks and others with selectors giving access to one group of trunks only, a system can be arranged for different ranges of service, the telephone users of lesser importance being restricted to conversations in one telephone system, those of greater importance being able to obtain connections to a number of systems. In private branch exchange systems, for instance, the telephone users of greater importance would be given access to the city exchange system as well as to the private exchange system, while stations of lesser importance would be given access to the private exchange system only.

In the drawing 1 represents a trunk hunting selector having movable contact arms 5, 6, 7 arranged to be rotated over sets of bank contacts 2, 3, 4, and 2¹, 3¹, 4¹ by a turning magnet 8 with the aid of a ratchet and pawl mechanism not shown. Each of the sets

of contacts 2, 3, 4 is connected to the wires representing a trunk 9 and each set of contacts 2¹, 3¹, 4¹ forms the terminals of a trunk 10. The trunks 9 and 10 lead to different telephone systems, *e. g.* trunks 9 are represented as leading to group selectors and 10 are supposed to be leading to an operating position 12 in a system separate from that to which the group selector 11 belongs. There may, of course, be any number of trunks 9 or 10 in a group. In the drawing, sufficient bank contacts are shown for a group of three trunks leading to three selectors 11 and for a group of two trunks 10 leading to an operator's position or positions 12.

13 represents the test relay of the selector 1; 14 is the relay that is connected between the limbs 18, 19 of the subscriber's line and 20 that gives the subscriber 70 control over the test circuits. The relay 14 has contacts 20 and 21 that act in response to a comparatively feeble current flowing through the relay windings and a contact 22 that requires 25 a comparatively strong current to close it.

15 is a relay controlled by relay 14 and its function is to change the circuits of the test relay 13 so as to stop the testing action of this relay, while the contact arms 5, 6, 7 are 30 traveling over a particular group of trunks, *e. g.* 9, and to recommence testing on the next group being reached.

16 is a line relay under the control of the controlling station or subscriber 70. The 35 subscriber's station is represented merely by a resistance 71 and a key 72 for short circuiting this resistance, it being assumed that, on the subscriber taking his receiver from the switch-hook (not shown), the 40 usual apparatus required for talking and hearing is inserted in the loop, *i. e.* between the wires 18 and 19.

55 is an off normal switch that is closed the moment the selector 1 leaves its normal position. It is assumed that the subscriber 70 has a selector controller or impulse transmitter of the well-known finger wheel type or of any other suitable kind, this device not being shown in the drawing.

50 The significance of the other parts shown in the drawing and not described above will become clear from the description of the operation of the selector. When the subscriber closes the line circuit 18, 19 by removing his receiver from the switchhook, a current is caused to flow over the following path:— from the negative pole of battery, line relay 16, armature contact 23, line 18, resistance 71, at subscriber's station 70, line 19, contact 24 to the positive pole of the battery. The line relay 16 thereupon attracts its armature and closes the circuit of the turning magnet 8, which includes an interrupter 17. The current through the turning magnet flows from the positive pole of

the battery, through interrupter 17, windings of magnet 8, armature contact 25, armature contact 27, to the negative pole of battery. In response to each impulse caused by the interrupter 17, the ratchet and pawl device actuated by the turning magnet 8 moves the contact arms 5, 6, 7 of the selector around step by step, over the sets of contacts 2, 3, 4 in search of an idle trunk 9. The moment an idle trunk is found a current will flow 70 from the negative pole of the battery at the group selector 11, through a resistance 28, bank contact 4, test arm 5, windings of test relay 13, armature contact 29, armature contact 30 to the positive pole of the battery. The completion of this circuit will cause the 75 energization of the test relay 13 and the subsequent attraction of its armatures. Thus contact 23 will be opened and the circuit containing the line relay 16, previously completed, will be interrupted and the line relay 16 deenergized. The release of the line relay armatures will open the circuit containing the turning magnet 8 at contact 27, and also the circuit containing the test relay 80 13 at contact 29; therefore the operation of the turning magnet 8 will cease and thus the contact arms 5, 6 and 7 will remain upon the idle trunk selected. The test relay 13 is not deenergized by the breaking of the circuit at contact 29 on line relay 16, as this 85 part of the test relay circuit is substituted by a circuit which may be traced from the winding of relay 13, through contact 60 and contact 45 to the positive pole of the battery. By closing the contact 31, the test magnet 13 short circuits a part of its own winding 90 and thus reduces the potential at the test bank contacts 4 so as to render the seized trunk engaged. If the calling subscriber 70 95 desires a connection through the group selector 11, he will cause selecting impulses to flow through the line by working his selector controller or impulse transmitting device immediately after raising his receiver. In 100 the assumed system these impulses will be caused by interruptions in the loop 18—19 and will act upon controlling devices in the group selector 11, which as they form no 105 part of this invention, are not shown.

110 It must now be explained that the test relay in attracting its armatures closed a circuit containing relay 14, which may be traced as follows: from the positive pole of the battery through the three armature contacts 32, 33, 34, relay 14, armature contact 20, armature contact 35, resistance 40 and the negative pole of the battery. The armature contacts 32, 33 and 34 are so adjusted 115 that contact 32 will be completed before the contact 34 is broken. Due to the action of this make before break spring combination, the circuit containing relay 14, just traced, will be closed momentarily only, and relay 14 will receive but a momentary actuation. 120

However, the operation of relay 14 will close contacts 21 and 36. By closing these contacts the relay inserts its winding in a circuit including a battery and the subscriber's loop, which may be traced from the positive pole of the battery through armature contact 36, armature contact 37, line wire 19, resistance 71, line wire 18, wire 38, contact 21, relay winding 14, resistance 39 and the negative pole of the battery. This circuit will be completed before the circuit caused by the momentary actuation of relay 14 is broken at contact 20, since contact 21 will be closed before contact 20 is opened.

10 The current that will flow through the relay 14 at the moment of its actuation by the closure of the contacts 32, 33, 34 will be sufficiently weakened by resistance 40 to prevent closing of contact 22. After the relay 14 has inserted its winding in the line circuit 18, 19 the resistance 71 also reduces the current strength sufficiently to prevent the closing of contact 22. If the line circuit is now opened by the subscriber interrupting 20 the loop in the act of sending in selecting impulses the relay 14 will be deenergized and the contacts 21 and 36 reopened, leaving a clear connection from the subscriber's line 18, 19 through the contacts 37 and 41 to the 25 group selector. If the subscriber instead of immediately sending in his selecting impulses first closes the contact 72 and short-circuits the resistance 71 at his station, the current flowing through the relay 14 will be 30 strengthened sufficiently to cause it to pull up its heavier armature and to close the contact 22. This will excite the relay 15 through the following circuit: from the positive pole of the battery through contact 40 22, relay 15, off normal switch 56, which is now closed, to the negative pole of the battery. The relay 15 will attract its armatures and close the contacts 42, 43 and 44 and open the contacts 45 and 30. Circuit 45 changes are effected hereby, that cause the test relay 13 to release its armatures. It will be remembered that the test relay was being excited by a current flowing from the positive pole of the battery through the contact 45, winding of the relay 13, to the negative pole of the battery at the group selector. By the contact 45 being opened and contact 43 closed, the connection to the test relay 13 is changed from the positive to the negative pole of the battery, and thus the same pole of battery is applied to both ends of the winding of the test relay 13. Hence the test relay is deenergized and the circuit for the turning magnet is again closed by a current 50 flowing from the positive pole of the battery through the interrupter 17, turning magnet 8, contact 25, contact 27 to the negative pole of the battery. Contact 27 is, of course, closed again, for as soon as the test relay 60 13 releases its armatures the line relay 16 will again be energized by current flowing through the subscriber's loop.

As the test wires of all the trunks 9 are connected through a resistance 28 to the negative pole of the battery, the test relay 70 will have the same pole of the battery applied to each end of its coil as long as the contact arms 5, 6, 7 traverse sets of bank contacts 2, 3, 4 connected to trunks leading to group selectors 11. The moment the bank 75 contacts 2¹, 3¹, 4¹ are reached the test relay 13 will commence testing again, because the test wires 4¹ are connected through resistances 55 to the positive pole of the battery. The moment a free trunk is found the test 80 relay will be excited by a current flowing from the positive pole of the battery through a resistance 55, contact 53, armature 54, test contact 4¹, test contact arm 5, test relay 13, armature contact 29, armature contact 44 to 85 the negative pole of the battery. The test relay in attracting its armatures opens the circuit of the turning magnet as before, and connects the subscriber's loop 18, 19 through the contacts 41 and 37 to the talking wires 90 45, 46 and to the contact arms 6, 7 which now extend the connection through the wires 47, 48 of the trunk 10 to a relay 49 at the operator's position 12. The relay 49 will now be excited by a current flowing from 95 the positive pole of the battery through the wire 47, contact 2¹, contact arm 7, wire 46, armature contact 37, wire 19, subscriber's station, wire 18, contact 41, wire 45, contact arm 6, bank contact 3¹, wire 48 of trunk 10, 100 winding of relay 49 to the negative pole. The relay 49 attracts its armature and closes the contact 50 included in the circuit of a calling lamp 51, thus attracting the attention of the operator to the call. The operator answers the call in the manner usual in manual exchanges by inserting a plug in a jack 52.

It must be pointed out that the armature 110 54 and its contact 53 are so arranged that the attraction of this armature will not open contact 53. When the subscriber at the finish of the connection replaces his receiver and thus opens his line loop, the relay 49 releases its armatures. The armature 54 in 115 moving back to its normal position momentarily opens the contact 53 and deenergizes the test relay 13, which again closes the circuit of the turning magnet 8 at its contact 25, so that current impulses will flow 120 through the turning magnet from the positive pole of the battery through interrupter 17, turning magnet 8, contact 25, contact 26, off normal contact 56 to the negative pole of the battery. As the circuit of the test relay 125 13 is now open at the contact 29 of the line relay the test relay will not test for idle trunks and the turning magnet will continue stepping the contact arms 5, 6, 7 from one set of bank contacts to the next until the 130

contact arms are in their normal position, when the off-normal switch 56 will be opened and the circuit of the turning magnet 8 interrupted. The opening of the off-normal switch 56 also opens the locking circuit of the relay 15, and thus causes all the parts of the selector to return to their normal position. It will be clear that another group of trunks similar to 9 could be arranged beyond the group 10, and that the contact arms 5, 6, 7, after they have selected a free trunk 10 could be caused to move on again and to travel over all the trunks 10 without testing until the next group of trunks similar to 9 is reached, where the testing function would commence again. This restarting of the selector after the contact arms have chosen a free trunk 10 in the second group could be brought about by a switch located at the point S in the wire leading from the contact 42 of the relay 15 to the positive pole of the battery. If this switch S were placed at the controlling station 70 so that it could be opened at will at the station, the switch could be caused to re-commence its travel by opening switch S and causing the relay 15 to release its armatures. The positive pole of the battery would then again be connected through the contact 30 to the coil of the test relay 13 and as the same pole of the battery is connected through the contacts 53 at the operating positions 12 to the other end of the coil 13, the test relay would cease to test until it reached the next group of trunks similar to 9 that have the negative pole of the battery connected to them through resistances 28.

Although a selector with only one row of contacts has been described, it will be clear to all who are skilled in the art that selectors on the same principle could be built having several rows of contacts and a selecting magnet for causing the contact arms to hunt in any one of the several rows.

45. In a private establishment having a private branch exchange, the telephone users generally wish to call another party connected to the private exchange, and do not so often make calls through the public or 50 city exchange. In an establishment of this kind there are usually two classes of service, most of the telephone users being confined to telephonic communication within the private establishment, and others being provided with connecting facilities for both the private establishment and the public exchange. The trunk hunting selector described above is peculiarly adapted for a private system of this description; the subscribers that are to be allowed unrestricted connecting facilities would be provided with a trunk hunting selector as described above, from which one group of trunks lead to 55 selectors of the private exchange, and another group of trunks lead to the public

exchange. The subscribers that are to be allowed connections through the private exchange only would be provided with trunk hunting selectors which will connect with but one group of trunks, these trunks being 70 wired to the selectors of the private branch exchange.

I claim:

1. A trunk hunting selector for telephone systems comprising movable contacts, 75 groups of fixed contacts arranged in a single row, each of the said groups of contacts being connected to a different group of trunks, driving mechanism for driving said movable contacts over said row of contacts, 80 means for causing said mechanism to stop the movable contacts at an idle trunk in a group and a switching relay under the control of the subscriber which will cause the advance of said movable contacts over said 85 fixed contacts in the group whether busy or idle.

2. A trunk hunting selector for telephone systems, comprising movable contacts, groups of fixed contacts each connected to 90 a different group of trunk lines, said groups of contacts being arranged in a single row, mechanism for driving said movable contacts over said row of fixed contacts, means for causing said mechanism to stop the movable contacts at an idle trunk in a group, means for causing the movable contacts to re-commence traveling over any contacts in the said group whether busy or idle and means for causing the said movable contacts to stop at a free line in the next group 100 of contacts.

3. A trunk hunting selector for telephone systems comprising movable contacts, groups of fixed contacts each connected to 105 a different group of trunk lines, said groups of contacts being arranged in a single row, mechanism for driving said movable contacts over said row of fixed contacts, a test electro-magnet controlling said driving 110 mechanism so as to cause it to stop acting when the selector reaches a free trunk in a group, a line leading from the said trunk hunting selector to a controlling station, an electro-magnet under the control of the said 115 station for changing the circuit of the said test electro-magnet so as to render the driving mechanism uncontrollable by the said test electro-magnet until the said movable contacts reach the next trunk group. 120

4. A trunk hunting selector for telephone systems comprising movable contacts, groups of fixed contacts arranged in a single row, each of the said groups of contacts being connected to a different group of trunks, a 125 single metallic controlling circuit extending from said trunk hunting selector to a controlling station, driving mechanism for driving said movable contacts over said row of contacts, means for causing said mecha- 130

nism to stop the movable contacts at an idle trunk in a group, and means to cause the advance of said movable contacts over said fixed contacts in the group whether busy or 5 idle.

5. A trunk hunting selector for telephone systems comprising movable contacts, groups of fixed contacts arranged in a single row, each of the said groups of contacts being 10 connected to different groups of trunks, driving mechanism for driving said movable contacts over said row of contacts, a controlling circuit leading from said trunk hunting selector to a controlling station, a test 15 electro-magnet for causing said mechanism to stop the movable contacts at a free trunk, a second electro-magnet connected to said controlling circuit after the stopping of the movable contacts, means in the controlling 20 circuit for causing said second electro-magnet to restart the traveling of the said movable contacts.

6. A trunk hunting selector for telephone systems comprising movable contacts, groups 25 of fixed contacts arranged in a single row, each of the said groups of contacts being connected to a different group of trunks, driving mechanism for driving said movable contacts over said row of contacts, a controlling 30 circuit leading from said trunk hunting selector to a controlling station, a test electro-magnet for causing said mechanism to stop the movable contacts on a free trunk, a second electro-magnet connected to said 35 controlling circuit on the stopping of the movable contacts, an interrupter in the controlling circuit for causing the disconnection of the said second electro-magnet from the said controlling circuit when this latter 40 is extended to a free trunk.

7. In a telephone system, trunk hunting 45 selectors comprising movable contacts, groups of fixed contacts arranged in a single row, each of the said groups of contacts being connected to a different group of trunks, driving mechanism for driving said movable contacts over said row of contacts, means for causing said mechanism to stop the movable contacts on an idle trunk in a group, 50 a switching relay under the control of the subscriber which will cause the advance of said movable contacts over said fixed contacts in a group whether busy or idle, and means to select the first idle trunk in the 55 next group.

8. In a branch exchange telephone system, a trunk-hunting contact arm, a test circuit therefor, a group of fixed contacts, trunk lines connected thereto, a second group 60 of fixed contacts, trunk lines connected thereto, means for advancing said contact arm upon the initiation of a call to an idle trunk in the first group, means at the controlling station for automatically selecting 65 a party over said trunk, and alternate means

at the substation for automatically advancing said selector to the next group by rendering the test circuit inoperative and for hunting an idle trunk in said second group.

9. In a branch exchange telephone system, groups of fixed contacts, trunk lines leading therefrom directed to different classes of service, trunk-hunting contact arms coöperating with said contacts, means at the calling station to select one class of 70 service, alternate means at the substation to subsequently select another class of service, a bridged switching relay under the control of said second means, and means operated by said relay for switching said contact 75 arms from one class of service to the next.

10. In a branch exchange telephone system, a group of fixed contacts, trunk lines connected thereto, a second group of fixed contacts, trunk lines connected thereto, 80 trunk-hunting contact arms coöperating with said contacts, a test circuit therefor, means for advancing said contact arms, means for stopping said contact arms on an idle trunk, a bridged switching relay which 85 is partially operated by said means, means at the calling station for deenergizing said relay, means at the substation for increasing the flow of current in the line circuit and causing the complete operation of said relay, and means controlled by said relay to 90 automatically advance said contact arms to the next group of contacts by rendering the test circuit inoperative and to hunt an idle 95 trunk in said next group.

11. In a branch exchange telephone system, groups of fixed contacts, trunk lines directed to different classes of service connected to said contacts, a traveling trunk-hunting terminal for testing the condition 100 of said contacts, and means at the calling station to control the terminal test circuit to render it inoperative for one class of service and operative for another class of service.

12. In a branch exchange telephone system, a group of fixed contacts, trunk lines leading therefrom directed to a particular class of service, a second group of fixed contacts, trunk lines leading therefrom and directed to a different class of service, trunk-hunting contact arms, a test circuit therefor, means for placing the test circuit under the control of the subscriber after the selection of an idle trunk in the first group, 115 and means to automatically advance said contact arms to the next group of contacts by rendering the test circuit inoperative and for hunting an idle trunk in said next group.

13. In a branch exchange telephone system, groups of trunk lines provided for different classes of service, a selector, means to automatically advance it to hunt and select an idle trunk in any group, a test circuit therefor, means provided at the substation 125

100

110

120

125

130

to subsequently render the test circuit inoperative, means for advancing said selector to the next group, and means for automatically hunting an idle trunk in said

5 group.

14. In a trunk selector, terminals for different classes of trunks, traveling contacts for testing said terminals, means to associate said traveling contacts with a set of 10 idle terminals of one class, and means associated with said contacts to subsequently

cause them to test over busy and idle terminals of that class and connect with the first idle terminal of another class.

In witness whereof, I hereunto subscribe 15 my name this 29th day of November A. D. 1912.

FRITZ ALDENDORFF.
